The ornamental design for an operation panel for controlling machine tools, as shown and described.

DESCRIPTION

FIG. 1 is a perspective view of an operation panel for controlling machine tools showing our new design;

FIG. 2 is a front view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a rear view thereof.

The broken lines shown in the drawings are for illustrative purposes only and form no part of the claimed design.
